United States Patent

Des. 240,150
Patented June 1, 1976

240,150

INFLATABLE BOXING GLOVE

Jimmy Kowk Wing Lau, 2-1, Section 2, Shihchuan Road,
Panchiao, Taipei Hsien, Taiwan, Republic of China

Filed June 26, 1974, Ser. No. 483,281

Term of patent 14 years

Int. Cl. D21—02

U.S. Cl. D34—15 DD

FIG. 1

FIG. 2

FIG. 3

FIG. 1 is a top front and side perspective view of an inflatable boxing glove;

FIG. 2 is a front elevational view thereof;

FIG. 3 is a right side elevational view thereof;

FIG. 4 is a left side elevational view thereof;

FIG. 5 is a top plan view thereof;

FIG. 6 is a bottom plan view thereof; and

FIG. 7 is a rear elevational view thereof.

I claim:

The ornamental design for an inflatable boxing glove, as shown.
